UNITED STATES PATENT OFFICE.

JAMES ROCHE, OF TERRYVILLE, CONNECTICUT, ASSIGNOR TO THE EAGLE
LOCK COMPANY, OF SAME PLACE.

DESIGN FOR A PADLOCK.

SPECIFICATION forming part of Design No. 25,664, dated June 23, 1896.

Application filed May 11, 1896. Serial No. 591,174. Term of patent 7 years.

To all whom it may concern:

Be it known that I, JAMES ROCHE, of Terryville, in the county of Litchfield and State of Connecticut, have invented a new Design for 5 a Padlock; and I do hereby declare the following, when taken in connection with the accompanying drawing, and the letters of reference marked thereon, to be a full, clear, and exact description of the same, and which said 10 drawing constitutes part of this specification, and represents a perspective view of my newly-designed padlock.

This invention relates to a design for a padlock; and the design consists in the configuration shown in the accompanying illustration, 15 and herein described.

My newly-designed padlock has a body or

shell A, which is triangular in general form, although its upper corners are cut off, as at A' A'. The point of the triangle forms the 20 lower end of the body, while the hasp or bail B is applied to the straight side of the triangle which forms the upper edge of the body.

I claim—

The design for a padlock as shown in the 25 accompanying illustration and as described herein.

In testimony whereof I have signed this specification in the presence of two subscribing witnesses.

JAMES ROCHE.
